UNITED STATES PATENT OFFICE.

HENRY C. MILLER, OF WATERFORD, NEW YORK.

CONTROLLING MECHANISM.

1,077,152.

Specification of Letters Patent. Patented Oct. 28, 1913.

Application filed February 6, 1908. Serial No. 414,552.

To all whom it may concern:

Be it known that I, HENRY C. MILLER, a citizen of the United States, residing at Waterford, in the county of Saratoga and State of New York, have invented certain new and useful Improvements in Controlling Mechanism, of which the following is a specification.

This invention relates to improvements in talking machines, and more particularly the governor and stopping mechanism.

The prime object of the invention is to provide a governor for a talking machine which may be set previous to the starting of the machine, to uniformly produce the selection to be rendered.

A further object of the invention is to provide simple and effectual automatic means for stopping the motor when the end 20 of the record groove is reached.

The invention also relates to the specific details of construction and arrangement of parts, all of which will be hereinafter referred to and particularly pointed out in 25 the claims.

In the drawings: Figure 1 is a vertical section of a portion of a motor for a talking machine, with my improvements applied thereto. Fig. 2 is a plan view of the same 30 with the record support removed. Fig. 3 is a vertical section illustrating a slightly different form of my invention. Fig. 4 is a detail plan view of the same. Fig. 5 is a similar view, showing the automatic stopping trip in normal position. Fig. 6 is a detail section of a slight modification.

The numeral 1, indicates a frame from which depend hangers 2, supporting a shaft 3, carrying a motor 4, comprising a spring 40 barrel 5, a worm gear 6, and means for making the operation of winding the motor noiseless, the same being indicated at 7. Depending from the frame 1, is a hanger 8, formed at its lower end with an opening 9, to receive the centering pin 10, the upper 45 end of the latter being of conical formation. The pin 10, is rigidly held in position by a set screw 11. Supported on the conical end of the pin 10, is a vertically disposed shaft 12, extending above the casing, and provided at its upper end with a transverse slot 13, below which are threads 14.

A sleeve 15, is mounted on the shaft 12, and is threaded at its upper end at 16, to 55 engage the thread 14, on the shaft, and it is

also provided with a worm 17, with which the worm gear 6, meshes. Mounted near the upper end of the sleeve is a plate 18, having an enlarged portion 19, to form a counterbalance, and a reduced portion to receive a 60 centrifugal weight 19', pivoted at 20. The plate 18 operates in an annular flange 21, extending upwardly from the frame 1, the interior surface serving as a track against which a friction strip 22, on the weight 19', 65 contacts to retard the speed of the motor. Above the plate 18, and mounted on the sleeve 15, is a record support 22', formed with a cut out portion or way 23. Extending from the outside toward the center of 70 the record support and across the cut out portion 23, is a pin 24, held in place by a collar 25. The pin is threaded to receive a threaded nut 26, designed to operate in the cutaway portion 23, and provided with a 75 depending stud, to which is secured one end of a spring 27, connected at its other end to a pin or stud 28, projecting from the weight 19'. The end of the pin 24, extends beyond the periphery of the record support 80 22', where it is knurled to provide a finger grip for adjusting the tension of the spring to regulate the centrifugal movement of the weight 19'. This part of the invention relates to the governing mechanism, and is 85 constructed and arranged so as to make it necessary to set the governor preceding the starting of the reproduction of a selection, and to thereby avoid irregularities in the piece being reproduced, so common with 90 talking machines now in use. To increase the speed of the motor, the pin 24, is turned so as to move the nut 26, outwardly, which movement increases the tension of the spring 27, which obviously requires greater speed 95 of the plate 18, to throw the weight outwardly in contact with the flange 21. To slow up the speed the pin 24, is turned in the opposite direction to feed the nut 26, toward the center, which relieves tension 100 on the spring 27, and thereby allows the weight 19', to be thrown outwardly more readily.

A boss or braking surface 40, (Fig. 1) depends from the frame 1, which co-operates 105 with a disk 41, carried by the sleeve 15, a suitable wearing surface such as leather or the like being interposed between said two surfaces. This detail of construction is the means I employ for stopping the motor at a 110

determined point, which is automatically controlled by a tripping device actuated by the stylus.

A cap 42, having a centrally disposed opening with a cross bar 43, is fitted over the upper end of the vertical shaft 12, the cross bar engaging the slot 13. An arm extends outwardly from the cap and has pivoted to it a lever 44, having a stop 45, adapted to contact with the arm on the cap to cause the two elements to move simultaneously at the proper time.

The cap 42, and lever 44, are turned in the direction of the arrow A, Fig. 4, to the dotted line positions through the cross bar and slot connection which also turns the shaft 12 and through the screw threads 14 and 16 feeds the sleeve 15, and the disk 41, downwardly away from the boss 40. The lever 44, is turned on its pivot until its free end crosses the last end of the groove of the record 47. As the record is revolved it feeds the stylus 48, toward the shaft 12, and when the last groove is reached it contacts with the free end of the lever 44, and causes it to turn on its pivot until the stop 45, contacts with the arms projecting from the cap 42, as shown in full lines in Fig. 4. Immediately this position of the parts is assumed the movement of the shaft 12, is retarded, but the sleeve 15, continues to revolve and is being elevated by reason of the threads 16, engaging the threads 14, until the disk 41, contacts with the boss 40, which stops the motor at the time the end of the record groove is reached.

The lever 44, can be set to accommodate records of any varying lengths, which makes it possible to automatically stop the machine at the end of any size record.

In Fig. 3, I have shown a slightly different form of my invention which only differs from that shown in Fig. 1, in minor details of construction, however, the basis of the operation is substantially the same. In this figure the shaft 50, does not move vertically, but is formed with an internally threaded opening at its upper end, indicated at 51, and a threaded pin 52, is fitted in said opening. The pin 52, is provided at its upper end with a slot 53, and a cap 42, such as previously described co-operates with it. An opening 54, is formed in the counterweight 19, and the shaft 50, through which passes a sliding dog 55, the inner end of which is of conical formation and is in the path of movement of the conical end of the pin 52, while its outer end is normally in contact with the inner edge of the weight 19'. In this construction when the cap 42, is revolved it feeds the threaded pin 52, downwardly, causing its beveled end to force the dog 55, outwardly in contact with the weight, until the latter impinges the inner wall of the annular flange 21, thereby stop-

ping the motor in substantially the same manner as previously described.

For use with ordinary machines the invention may be constructed as shown in Fig. 6, wherein the post 60, is bifurcated, and mounted thereon is a sleeve 61, having screw threads 62. Loosely mounted on the sleeve is an arm, which is the equivalent of the cap 42, previously described, and over this arm and engaging the thread 62, is a nut 64, having a piece of leather or the like 65, interposed between it and the arm 63. In this construction when the arm 63, is held against turning by the stylus the friction between it and the nut is sufficient to cause the latter to turn on the thread 62, which moves it down until it binds and thereby prevents further movement of the shaft 60, and stops the motor.

In using the governor, the operator knowing the approximate speed necessary to produce the best result in playing a selection, adjusts the position of the spring connected to the weight before the record is applied.

When applying a record, cap 42 is removed to permit the record to be slipped over the center shaft, and then the lever 44, is properly adjusted with reference to the groove as previously described, and the hand brake indicated at α , is released and the machine is started. Immediately, however, the stylus contacts with the lever 44, the automatic stopping device is brought into operation as described, and the machine is stopped without any shock to the mechanism.

The record support 22, is formed with an opening 78, directly over a cavity 79, in the counter-balance 19, and from the cavity leads a duct 80, to the sleeve 15, and a groove or duct 80', permits oil dropped into the cavity to flow down the sleeve to oil the worm and its gear. The lower end of the sleeve is provided with a cup 82, formed with a passage 83. The oil finding its way down the outside of the sleeve is caught by the cup and is then directed to the conical ends of the pin 11, by the passage 83, thereby permitting of the oiling of the parts.

What I claim is:

1. In combination, a stationary frame having a stationary annular flange, a motor including a revolving shaft, a plate revolving with the shaft, a weight pivoted to the plate, a second plate revolving with the shaft, and formed with a guide way, a threaded element mounted in the guide way, a nut mounted on the threaded element, a spring connected to the nut and the pivoted weight, the weight contacting with the annular flange when it is thrown out by centrifugal force, and an automatic stopping device acting on the weight to stop the movement of the shaft.

2. In combination with a frame having a

stationary annular flange, a motor including a revolving shaft, a plate having a counterbalanced weight pivoted to the plate, an element which may be turned, and a spring 5 connected to the revoluble element and the pivoted weight, the turning of the element causing the end of the spring attached thereto to be moved at an angle and thereby increase or decrease the tension of said 10 spring, the outer edge of the pivoted weight contacting with the annular flange when said weight is thrown out by centrifugal force, and an automatic stopping device acting on the weight to stop the movement of 15 the shaft.

3. In combination, a frame having a stationary annular flange, a motor including a shaft, a plate having a counterbalance and revolving with the shaft, a weight pivoted 20 to the plate, a second plate revolving with the shaft and formed with a guide way, a screw mounted in the plate, a nut mounted on the screw and traveling in the guide-way, a spring connected with the nut and the 25 weight to place the weight under tension, the outer edge of the weight contacting with the annular flange when said weight is thrown by centrifugal force, and an automatic stopping device acting on the weight 30 to stop the movement of the shaft.

4. In combination, a stationary annular flange, a motor including a shaft, two plates mounted on the shaft, a weight pivotally mounted on one of the plates to coöperate 35 with the annular flange, an adjusting device on the other plate and extending beyond the outer edge of said plate, a spring connecting the adjusting device and the pivoted weight, and an automatic stopping device 40 coöperating with the weight.

5. In combination, a frame having a flange, a motor including a revolving shaft, a governor coöperating with said shaft, and including a weight, an automatic stopping 45 device revolving with the shaft, a connection interposed between the automatic stopping device, and the weight to force the latter into contact with the flange when the automatic stopping device is operated.

50. 6. In combination, a frame having a stationary annular flange, a revolving shaft, a governor revolving therewith, including a plate and counter-weight, a pivotally mounted weight carried by said plate, a movable 55 element on the plate, means for adjusting the movable element, said means extending beyond the plane of the edge of the plate to form a finger piece, a spring connected to the movable element and the piv-

otally mounted weight, the edge of the pivotally mounted weight contacting with the annular flange when said weight is thrown out by centrifugal force, and an automatic stopping device acting on the weight to stop the movement of the shaft. 60

7. In combination, a stationary frame formed with an annular well, a shaft mounted centrally therein, a plate rigidly mounted on the shaft, a weight pivotally mounted on said plate and in a plane with the wall of the annular well, means for revolving the shaft, a second plate rigidly attached to the shaft above the frame, spring adjusting means mounted on the second mentioned plate, a spring connected to the spring adjusting means and the weight, and automatic means coöperating with the shaft to stop the same. 75

8. In an apparatus of the class described, the combination of a shaft, a stationary 80 plate provided with an opening through which the shaft passes and having an annular flange, a plate secured to the shaft and having a counterbalance, a weight pivoted to said latter plate and coöperating with the annular flange, a second plate mounted on the shaft and provided with a guideway, a screw extending through the guideway, a block formed with a threaded opening and operating in the guideway, the screw engaging the threaded opening in the block, a spring connected to the block and the weight, whereby to control the centrifugal movement of the weight, a threaded extension mounted in the shaft, and means connected to the threaded extension to hold the same against movement at a predetermined period and stop the revolution of the shaft. 85

9. In an apparatus of the class described, the combination of a plate formed with a 90 central opening and an annular flange, a shaft extending through the opening and provided with a central threaded opening, a plate secured to the shaft and provided with a counterbalance, a weight pivoted to the plate, a second plate secured to the shaft, means for regulating the centrifugal movement of the weight, a threaded extension fitting in the threaded opening in the shaft, and means for preventing the threaded extension from turning at a predetermined time to stop the movement of the shaft. 100

In testimony whereof I affix my signature in presence of two witnesses.

HENRY C. MILLER.
